UNITED STATES PATENT OFFICE.

PERRY J. WIELAND, OF FARMERSVILLE, OHIO.

AUTOMATIC GATE.

SPECIFICATION forming part of Letters Patent No. 271,963, dated February 6, 1883.

Application filed October 3, 1882. (No model.)

To all whom it may concern:

Be it known that I, PERRY J. WIELAND, a citizen of the United States, residing at Farmersville, in the county of Montgomery and State of Ohio, have invented certain new and useful Improvements in Automatic Gates, of which the following is a specification, reference being had therein to the accompanying drawings.

10 My invention relates to swinging gates; and it consists in the construction and arrangement of its several parts, as will be hereinafter fully set forth, and pointed out in the claims.

15 In the drawings, Figure 1 is a general perspective view; Fig. 2, a rear elevation with the post broken off, showing an elevation of the hinge-post of the gate; Fig. 3, a perspective from the bottom side of the lower gate-hinge; Fig. 4, a perspective of the crank; Fig. 5, a 20 perspective of the latch; Fig. 6, a bottom plan of the lower hinge, and Fig. 7 a perspective of the crank in position.

25 A is the main sill, and extending at right angles from the end upon which the gate turns are the detachable supplemental sills A'. They are held in place by the bar a, one end of which is secured to one of the sills A', and passes over bolts or pins a' in the end of the sill A and side of the opposite sill A', as shown 30 clearly in Fig. 2.

Secured vertically to each end of the sill A are the latch-post A² and the hinge-post A³. The hinge-post is provided upon its upper portion with a hook, to which is pivoted the gate, 35 and upon its lower portion with a plate, B, having a horizontal projection, b, in which is cut a semicircular slot, b', as shown. The lower portion of the plate is recessed at b².

40 The turning post C of the gate is provided upon its upper portion with a plate, c, having cut through it +-shaped slots c', by means of which it is attached to the post and rendered capable of proper adjustment, as the gate shrinks or the post settles down, and projecting from its central portion is an eye-plate, 45 which fits over the hook in the hinge-post.

Attached to the turning post, below the plate c, is a rod, c², which extends downwardly parallel with the post, slightly separated from it, and passes through the semicircular slot b'. An offset projects from the lower portion of the gate and engages with the rod

c², and holds the gate in its vertical position. To the lower end of the rod c², immediately beneath the projection b, is secured the lock-plate c³, and on the inner side of this plate are lugs c⁴, which bear against the ends of the recess b², as shown in Figs. 3 and 6.

Pivoted to the under side of the plate are curved trips c⁵, the inner or convex sides of which bear against the face of the plate B, as shown. Attached to the free ends of the trips and extending therefrom in opposite directions are the rods which connect the gate swinging with the actuating mechanism.

65 The actuating mechanism is situated upon the supplemental sills A', which are suitably enlarged and recessed to accommodate said mechanism.

D is the crank, one end of which is bent 70 horizontally for a short distance, and is journaled to the sill at d. The other end is also bent horizontally and is journaled to the sill, and projects into a suitable recess, d', as shown.

Secured to the long end of the crank and 75 operating in the recess is the actuating-lever d², having pivoted in its end a button or guide, d³, to one end of which is secured the chain or rod which operates the gate. The outer end is bent over so as to bear against the top edge 80 of the lever d², and cause the guide to draw the chain to its full length when the crank is turned toward the gate, and turn upon its pivot and draw the chain only enough to bring the gate to a vertical position when the crank is 85 turned away from the gate. Also secured to the same end of the crank is the hinged elevating-lever d⁴. It is pivoted to the weight d⁵, so that when the crank is turned down by the carriage-wheel the weight is lifted, and after 90 the wheel has passed over it it drops back, causing the crank to turn up sufficiently to draw the operating rod or chain taut. A post is set up in front of the recess to prevent the wheel running into it, and a recessed guide- 95 post, in which travels the chain.

The rods e extend from the trips c⁵ to the guides d³, as shown. They are in two parts, the ends of each being flattened, corrugated, and clamped together, with capability of being 100 lengthened and shortened, as described.

The latch-post A² is provided with a latch, E, and the swinging post of the gate with a catch-pin, e, which engages with the latch.

The latch consists of a plate, c' , provided upon its lower end with a projection, c^2 , the top side of which has a central depression and bevels toward the edges, as shown in Fig. 5. 5 Pivoted to the plate are double-acting pawls c^3 , having curved lips, which meet and form an open space between them for the reception of the pin e . Above the pawls are placed pins e^4 , which limit their throw. 10 In the operation of the gate the normal position of the operating cranks is vertical. Upon the approach of a carriage the front wheel strikes the crank, which is turned down horizontally toward the gate, the lever d^2 depressed, actuating rod or chain e , drawn upon the trip c^5 , lifts the lugs on the lock-plate c^2 out of the recess, and the rod e is then drawn over to the side of the semicircular slot b' from which the carriage is approaching. This action 15 throws the turning post of the gate out of a vertical line and elevates the swinging end. The latch-pin e is lifted out of the pawls c^3 and the gate swings open in the opposite direction to that from which the carriage is approaching. 20 After the carriage has passed through, the crank on the opposite side is turned down away from the gate by the wheel, which operation causes the guide d^3 to turn on its pivot and draw the chain only sufficient to bring the 25 rod e^2 and the gate equidistant between the ends of the slot b' . The gate then swings between the posts and the latch-pin e passes under one of the pawls c^3 , is stopped by the outer one, and the gate is there held securely between the posts. 30 It is seen that the only way to release the gate is by raising the pin out of the pawls, 35

which can only be done by turning down one of the cranks, whereby the swinging post of the gate is elevated and the pin lifted out of the pawls. 40

What I claim is—

1. The combination, in a gate, of a hinge-plate secured to the hinge-post, formed with a slotted and curved projection, and recessed below said projection, with the gate having a rod secured to its pivot-post, said rod passing through the slot in the hinge-plate projection, and having a lock-plate secured to its lower end, said plate being formed with lugs which enter the hinge-plate recess, and further provided with pivoted trips which bear against the edges of said recess, and adapted to release the lugs and lock-plate when drawn upon, as shown and described. 45

2. The laterally-acting gate-hinge, formed of the combination of a plate secured to the hinge-post, said plate having a curved and slotted projection and a recessed lower portion, with a rod secured to the turning post of the gate, extending downwardly through the slot parallel with the gate, said rod having secured to its lower end a lock-plate having lugs which enter the recess in the hinge-plate, and trips to draw said lugs out of the recess, all 50 arranged to operate substantially as shown and described. 55

In testimony whereof I affix my signature in presence of two witnesses.

PERRY J. WIELAND.
